H. PRYM.
PRESS BUTTON.
FILED MAY 22, 1922.

Inventor:

Hans Prym

By Marks Clark

Atty's

UNITED STATES PATENT OFFICE.

HANS PRYM, OF STOLBERG, GERMANY.

PRESS BUTTON.

Application filed May 22, 1922. Serial No. 562,903.

To all whom it may concern:

Be it known that I, HANS PRYM, a subject of Germany, and residing at Stolberg, Rhine State, Germany, have invented a certain new and useful Press Button, of which the following is a specification.

It has already been proposed, in connection with press buttons, to arrange the sewing holes in a sunken position relatively to the surface of the disc of the press button parts in order to obviate a piling up of the sewing threads on the face of the disc of the button after repeated stitching. In the prior devices the sewing holes are formed by stamping out portions of the said disk of the button, the portions of the disk between the holes and the edge of the said disc being bent to form a support for the threads. This arrangement has certain disadvantages, one of which is that the faces supporting the threads have sharp edges which damage the said threads.

According to the present invention, this disadvantage is obviated by placing the sewing holes on the discs within the boundary of a ring fixed in the bent edge of the disc, the said ring being, in the socket part, a portion of the spring catch itself. The sewing threads are, therefore, caused to engage the ring and bear thereon, so that they are not damaged by sharp edges. The ordinary button in which the spring catch is placed in position by machinery, may be used with the present invention.

The accompanying drawing illustrates, by way of example, a construction according to the invention on an enlarged scale.

Figure 1 is a bottom plan view of the socket part.

Figure 2 is a vertical section on the line 2-2 of Figure 1;

Figure 3 is a vertical section through the head part;

Figure 4 is a plan view of the latter.

As illustrated in Figures 1 and 2, the edge *c* of the disc *a* of the socket part is preferably bent and flanged. The sewing holes are formed partly in the bent portion of the edge *c* and partly in the disc *a*, in

other words, and as shown in Figure 1, 50 the edge *c* and a portion of the disc *a* are cut away to form holes *b* so that no edge is left at those points and thus the threads do not pass over the disc *a*. The bent and flanged edge *c* receives a ring *d* of round 55 cross section which is preferably a portion of the spring catch member and also forms a support to the sewing threads *e*.

The sewing threads are passed over the uncovered portions of the ring *d* and are 60 not damaged thereby owing to its round cross-section. The material is preferably firmly pressed against the bent edge *c*.

Referring to Figures 3 and 4, the disc *a'* of the button proper is similarly provided 65 with a bent edge *c'* wherein a ring *d'* is located. The sewing holes *b'* are also formed by cut-out portions on the edge *c'* and disc *a'*, the method of securing the ring *d'* in position being identical to that resorting to for the socket part.

It is, of course not necessary that the extreme edge be cut out to form the sewing holes; the said edge may be left untouched and bent under the ring as in the present 75 case, and sewing threads will bear directly on the said ring.

Having now particularly described and explained the nature of my said invention and in what manner the same is to be performed, I declare that what I claim is—

1. In a press button, a disk having apertures sunk below its surface and adapted to receive the threads employed in securing the disk in position on a garment or the like, the edge of said disk being bent inwardly, and a ring secured in the bent edge of said disk and forming the outer boundary of said apertures, the portions of the bent edge adjacent the outer periphery of 85 said ring being cut away in order to permit the sewing threads to bear directly on said ring.

2. A press button as claimed in claim 1 in which a spring catch is integral with 90 said ring.

3. A press button including a disk having apertures sunk below its surface, a ring

connected to the edge of said disk and forming the outer boundary of said apertures, the edge portion of said disk being cut away adjacent said apertures to permit 5 the threads used in connecting the disk to a garment or the like to bear directly on said ring.

4. A press button as claimed in claim 3

in which said ring is of circular cross section.

In testimony whereof, I hereunto affix my signature in the presence of two witnesses.

HANS PRYM.
